UNITED STATES PATENT OFFICE

CARL PETER NELSON, OF FIRTH, IDAHO

DOOR LOCK

Application filed May 6, 1929. Serial No. 360,741.

This invention relates to door locks and is adaptable to swinging or sliding doors.

An object of the invention is to provide a door lock which is operable from either side 5 of the door and moreover provides for an independent locking means on the exterior of the door to prevent unauthorized use of the lock.

Further objects of the invention are to provide a lock of the character referred to, which is extremely simple in its method of assembly, thoroughly reliable in its operation, adaptable to all standard doors, strong, compact and durable, and comparatively inexpensive 15 to manufacture and install.

With the foregoing and other objects in view, the invention consists in the novel construction, combination, and arrangement of parts as will be hereinafter more specifically 20 described and illustrated in the accompanying drawings wherein is disclosed an embodiment of the invention, but it is to be understood that changes, variations and modifications may be resorted to, without departing 25 from the spirit of the claims hereunto appended.

In the drawings, wherein like reference characters denote corresponding parts throughout the several views:

30 Figure 1 is an inner side elevation of a sliding door and jamb, showing the device in accordance with this invention adapted thereto.

Figure 2 is a horizontal section of the door 35 and jamb illustrating, in top plan view, the block assembled therewith.

Figure 3 is a side elevation of the lock showing the assembly for adaptation to a swinging door, and

40 Figure 4 is an end view of the swinging door and jamb, showing an end view of the lock assembled thereon.

Referring to the drawings in detail, 5 indicates a sliding door and particularly the inner face thereof, while 6 indicates a jamb on the door frame.

The numeral 7 indicates a flat substantially rectangular plate secured by hold-fast devices 8 at the four corners thereof to the doors 5. Extending across the plate inter-

mediate the ends thereof is a yoke shaped guide strap 9 secured at its opposite ends to the marginal edges of the plate 7 by a pair of stove bolts 10, 11, and the nuts 12, 13 secured on the inner ends of the bolts 10, 11, which are countersunk below the inner face of the door 5. The bight portion of the strap 9 is at a plane parallel to the outer face of the plate and the legs 14, 15, thereof have the edges in abutment with the upper face of the plate, thereby providing a spaced guide-way 16 between the bight and the outer face of the plate 7. A combined latch and handle is indicated generally at 17, and is formed of a strap of metal formed in open rectangular configuration having an extension 18 at one end and inwardly projecting bar 19 at its other end extending through the plate 7. The threaded arm 19 is connected to the under-face of the plate 7 by means of a nut 20 counter-sunk in the inner face of the door 5. The inner side 21 of the combination handle and latch member 17 is slidably confined within the guide 15 and is rockably mounted on the plate 7 by means of the projecting arm 19.

A forked spring 22 is mounted on the outer face of the plate 7, having one leg 23 within the guide 16 by having the inner end thereof wrapped around the bolt 11 as at 24 and the end of the other leg 25 is movably confined within the guide 16 in abutting relation to one edge of the inner side 21 of the combined handle and latch member 17, whereby the member 17 is normally projected downwardly 80 against the action of the spring. Since an operating rod 26 extends through the door 5, the plate 7 and the inner end thereof extend through the guide strap 9 whereupon the operating rod is rotatable therein. The outer end 27 of the operating rod projects outwardly from the outer face of the door and is threaded to receive a pair of nuts 28, 29, between which is secured rigidly to the rod 26, an extension 30 projecting inwardly from the U-shaped handle 31.

The other leg 32 of the handle adjacent the lower end thereof is provided with an opening 33, for the purpose presently to be mentioned. The operating rod 26 extends through an opening in one end of the hasp 100

34, which is rigidly secured to the door 5 by means of a bolt 35 adjacent the other end thereof, and the hasp is formed with a right angled outwardly projecting arm 36, having an opening 37 which registers with the opening 33, to receive a padlock 38, which when in locked relation prevents the movement of the handle 31 with respect to the hasp 34.

Rigidly connected to the operating rod 26 by welding or other well known means is a cam arm 39, mounted in the guideway 16. The edge of the cam arm 39 abuts against the edge of the side 21 opposed to the spring leg 25, whereby the operation of the rod 26, by the handle 31, will move the member 17 against the action of the spring leg 25.

In the application of the device to the sliding door as shown in Figures 1 and 2, the keeper member indicated generally at 40 is mounted directly on the door jamb 6 in a plane parallel to the sliding movement of the door 5, whereas in Figures 3 and 4 with the keeper indicated generally at 40, the same is attached to swinging doors, and the keeper is disposed at right angles to its position for sliding doors. The keeper is the same whether used for sliding or swinging doors and consists of a flat-plate 41, having an outwardly projecting arm 42 and an outwardly inclining extension 43 formed on the end of the arm. The keeper plate 41 is secured to the outer face of the door jamb 6 for sliding doors illustrated in Figures 1 and 2, by means of screws 44 and 45, but when used for swinging doors, as illustrated in Figures 3 and 4, the keeper is secured by the same means to a block 6' on the door jamb. When the extension 18 strikes the extension 43 on the keeper, the combination latch and handle rides upwardly on the same and seats itself between the keeper plate 41 and the arms 42. To detach the extension 18 from the keeper 40, either the handle 31 on the outside or the combined latch and handle 17 on the inside 45 of the door may be turned whereby the extension 18 is moved in an arc free of the keeper. An abutment indicated generally at 46 is secured to the outer face of the plate 7 and prevents the spring 22 from forcing the cam arm 39 beyond that point. The abutment 46 consists of a threaded bolt 47 extending through the plate 7 and having the head thereof counter-sunk in the door. The nut 48 is threaded on the bolt and is screwed tight 55 thereon until it comes into engagement with the plate 7.

What is claimed is:

1. A door lock of the character referred to comprising a flat plate adapted to be rigidly secured on the inner side of a door, a yoke shaped guide strap mounted on the outer face of the plate, a combined latch and handle rockably mounted on the plate and slidable in the guide, a forked spring having one leg rigidly secured to the plate and the other in

abutment with said combined latch and handle, a keeper adapted to be mounted on a door jamb, and having an arm projecting outwardly for engagement with said combined latch and handle, an operating rod adapted to extend through the door and having its inner end rotatably supported by said plate and guide strap and its outer end terminating exteriorly of the outer face of the door, a cam arm rigidly mounted on said rod between said plate and guide strap and abutting said combined latch and handle, an abutment rigidly secured to said plate to limit the movement of said cam, a hasp adapted to be rigidly secured to the outer side of said door, a second handle rigidly secured to the operating rod for rotating the latter, and detachable means connected with the hasp and handle for locking the latter against movement.

2. A door lock of the character referred to comprising a flat plate adapted to be rigidly secured on the inner side of a door, a yoke shaped guide strap mounted on the outer face of the plate, a combined latch and handle rockably mounted on the plate and slidable in the guide, a forked spring having one leg rigidly secured to the plate and the other in abutment with said combined latch and handle, a keeper adapted to be mounted on a door jamb, and having an arm projecting outwardly for engagement with said combined latch and handle, an operating rod adapted to extend through the door and having its inner end rotatably supported by said plate and guide strap and its outer end terminating exteriorly of the outer face of the door, a cam arm rigidly mounted on said rod between said plate and guide strap and abutting said combined latch and handle, an abutment rigidly secured to said plate to limit the movement of said cam, a hasp adapted to be rigidly secured to the outer side of said door, a second handle rigidly secured to the operating rod for rotating the latter, and detachable means connected with the hasp and handle for locking the latter against movement, said combined latch and handle formed of a continuous rim having a side thereof slidable between the guide and plate engaging said keeper arm at its outer end, pivoted at its inner end to said plate and forming a gripper at its other side.

In testimony whereof I affix my signature.
CARL PETER NELSON.
